UNITED STATES PATENT OFFICE

AKOS ANDREW YERGA AND MIKE EVANOWFF, OF HAMMOND, INDIANA

ICE-BOX ATTACHMENT

Application filed August 31, 1927. Serial No. 216,699.

This invention pertains to doors, and more particularly to auxiliary or track doors for use on refrigerators or the like.

Difficulty has oftentimes been experienced in providing a means of egress and ingress through an opening which when not in use will be closed in such a manner as to prevent leakage (of fluid) past the closure. This is particularly true with reference to icebox doors. It is usual in iceboxes, particularly those used in meat business, to provide tracks or guideways into said icebox providing means for holding the meat on a truck supported and slideable on the tracks, but heretofore difficulty has been particularly encountered in preventing the leakage of the refrigerating fluid past these tracks.

It is therefore an object of this invention to provide means for preventing leakage of cold air past guideways provided in a refrigerator.

Another object is to provide means for permitting ingress and egress of securing means to a refrigerator, said first named means being controlled by the refrigerator door and/or the securing means.

Still another object is to provide means for permitting ingress or egress of securing means to a refrigerator which is capable of adjustment whereby it may be operated by the refrigerator door at selected positions.

A further object is to provide normally closed doors adapted to prevent leakage of the refrigerating medium past the guideways of a refrigerator, said doors being adjustable to permit movement of the track.

With these and various other objects in view, the invention consists of certain novel features of construction and operation as will be more fully described and particularly pointed out in the specification, drawings and claims appended hereto.

In the drawings, which illustrate an embodiment of the device and wherein like ref-

erence characters are used to designate like parts—

Figure 1 is a front elevation of a portion of an icebox embodying the device for preventing leakage past the track or guideway 50 associated therewith;

Figure 2 is a sectional plan taken substantially in the plane as indicated by the line 2—2 of Figure 1;

Figure 3 is a rear elevation of the device 55 shown in Figure 1, showing the relation of the operating mechanism and the doors in closed position;

Figure 4 is a sectional side elevation taken substantially in the plane as indicated by the 60 line 4—4 of Figure 3;

Figure 5 is a fragmentary rear elevation of the device shown in Figure 1, showing the relation of the parts and the doors in open position; and

Figure 6 is a sectional plan taken substantially in the plane as indicated by the line 6—6 of Figure 5.

An icebox 10 of any usual and preferred construction may be provided as at 11 with 70 an insulated door hinged as at 12 to the icebox. Track 13 is provided adjacent any of the free edges of the door 11 (shown at the top thereof in Figure 1), for permitting ingress and egress of a truck or yoke 14 provided with a carrying means such as the hook 15, said yoke being provided with a wheel or wheels 16 having rolling engagement with the track, said wheels being pivoted in any convenient manner such as at 17 to the yoke. 75 Assembly 18 is provided in the ice box adjacent the door 11 in way of and surrounding the track 13, said assembly being provided with means for the purpose of allowing ready ingress and egress of the yoke 14 but preventing leakage of the refrigerating fluid from the icebox 10. The assembly consists essentially of a U-shaped frame member 19 provided with lower tracks 20 and upper tracks 80

21 providing guiding means for sliding doors 85 90

22 and 23. Said doors may be of any convenient construction and may be insulated or not as desired. They are, however, preferably provided with insulating means 24 and 25 along the edges thereof, said means being of felt or other construction and being held in place by fastening means 26 which may be of strap and screw construction.

The insulation 24 and 25 is suitably shaped 10 to fit around the track 13, completely enclosing the same when the doors are in closed position, and said insulation is also suitably shaped to fit around brackets or guides 27, provided on both doors, so that leakage is 15 prevented around said brackets when the doors are in closed position. These brackets are preferably of arcuate shape and are secured to the doors by any means such as the bolts or screws 28 above the track and in way 20 of the path of the yoke 14.

Suitably shaped links 29 and 30 are pivoted to the frame as at 31 and 32 above the doors and extend downwardly and are loosely pivoted to the doors through slots 33 and 34 25 and any proper pin connection. A bifurcated link 35 is pivoted at 36 to a crank 37 disposed between the links 29 and 30, said crank being rotatable with a shaft 38 extending through the frame 19. The link 35 is provided with 30 arms 39 and 40 which are pivoted at 41 and 42 to floating links 43 and 44, said links being pivoted at 45 and 46 to links 29 and 30, respectively, intermediate their ends.

A contractile spring 47 is provided between 35 links 29 and 30 and secured thereto, tending of course to always urge doors 22 and 23 towards each other to closed position. A crank arm 48 is non-rotatably secured to the shaft 38, said crank being preferably urged 40 upwardly; that is, towards door closing position, by means of a spring 49 secured as at 50 to the crank and as at 51 to the frame 19. A flexible means 52 such as a cable or cord of any material is secured to the crank 48 at 45 one end thereof at 53 and said means passes around a roller 54 pivoted to the bracket 55 and thence down and is secured to an adjustable connection 56 on the door 11.

It will now be appreciated that when the 50 door 11 is opened, due to a pull on the flexible connection 52, the crank 48 will be moved in a counterclockwise direction. This of course will urge the crank 37 upwardly, in turn raising links 35, 43 and 44, thereby forcing links 55 29 and 30 away from each other, expanding the spring 47 and urging the doors 22 and 23 to open position, allowing passage of the yoke along the track into or out of the icebox. Should the door 11 then be closed, spring 60 49 will of course urge the crank 48 in a clockwise direction and spring 47 will serve to draw the links 29 and 30 toward each other, thereby closing the doors. Should the doors 22 and 23 be in closed position and should it 65 be desired to pass the yoke 14 from one side

to the other of said doors, and should the door 11 be in such position as to allow the passage of the yoke; that is, either fully opened or partially open without having operated the doors 22 and 23, it is only necessary to push the yoke against the arcuate fingers 27, forcing the fingers and consequently the doors apart, which it will be understood, will allow the passage of the yoke, the spring closing the doors after passage of the yoke. Further, 70 if in use it should be found convenient, necessary or desirable to adjust the doors, i. e., to move the track 13 either to one side or the other, that may be readily accomplished without changing the structure of the device because due to the slots 33 and 34 provided in the links and due to the pivotal and link connections between the crank 37 and the links 29 and 30, doors 22 and 23 may be pushed or slid along their tracks to accommodate variations in the position of the track without affecting the opening or closing of said doors, or any one of them, and any such variations will not materially affect the relative position of the parts and will not in any way 80 affect their operation.

It is to be understood that we do not wish to be limited by the exact embodiment of the device shown, which is merely by way of illustration and not limitation, as various and other forms of the device will of course be apparent to those skilled in the art without departure from the spirit of the invention or the scope of the claims.

We claim:

1. In a closure device the combination of a main door, a track extending on both sides of and above said door, slidable door means for normally closing the space around said track, means tending to close said door means, said means being controlled by operating means directly connected to and readily releasable from said main door.
2. In a device of the character described, the combination of a guideway, doors disposed on either side thereof and normally closing said guideway, means for operating said doors, said means including crank and link members for moving said doors, resilient means for maintaining said doors in closed position, and means for effecting movement of said doors without operation of said doors by said first named means.
3. In an icebox, the combination of a main door, a guideway disposed out of the path of said main door and extending into said icebox, doors disposed on either side of said guideway and normally closed around the same to prevent leakage around said guideway, adjustable means between said main door and doors for operating said doors, and means on said doors permitting independent operation of the same.
4. In a device of the character described, the combination of a main closure, closures

100

105

110

115

120

125

130

associated therewith and operated thereby, said last named closures being controlled by members permitting operation thereof irrespective of the position of said first named main closure.

5. In a device of the character described, the combination of a movable main closure, movable closures adjacent said main closure, crank operating means connected by lost motion means to said closures for operating the same, and connecting means between said crank operating means and said main closure whereby said main closure may be operated to operate said closures.

10 6. In a device of the character described, the combination of associated closures, operating mechanism for one of said closures connected in operative relation to another of said closures, said mechanism including a 15 pivoted member having a loose connection to said first named closure, crank members, one of said crank members being connected to said pivoted member, another of said crank members being connected to said second 20 named closure, connection means between 25 cranks, and means for normally maintaining the mechanism in closure closing position.

7. In a device of the character described, the combination of associated closures, operating mechanism for one of said closures connected in operative relation to another of said closures, said mechanism including a pivoted member having a loose connection to said first named closure, crank members, one 30 35 of said crank members being connected to said pivoted member, another of said crank members being connected to said second named closure, connection means between cranks, means for normally maintaining the 40 mechanism in closure closing position, and means for opening one of said closures without operating the other of said closures.

8. In a device of the character described, the combination of a closure, operating mechanism therefor including a pivoted member having a loose connection to said closure, connected crank members, one of said crank members being connected to said pivoted member and operable by another 45 50 crank member for operating said closure, and means for normally maintaining said closure in closed position.

9. In a device of the character described, the combination of a closure, operating mechanism therefor including a pivoted member having a loose connection to said closure, connected crank members, one of said crank members being connected to said pivoted member and operable by another crank member for operating said closure, means for 55 60 normally maintaining said closure in closed position, and means for opening said closure without operating said operating mechanism.

10. In a device of the character described, 65 the combination of a main closure, a guideway associated with said main closure and adapted for supporting articles to be moved past said main closure, said guideway being located out of the path of said main closure, closures adjacent said guideway and arranged to embrace the same when in closed position, operating mechanism for said closures including pivoted members loosely connected to said closures, connected crank members, one of said crank members being connected to each of said pivoted members and operable by another of said crank members, said last named crank member being operatively connected to said first named main closure.

70 75 80 85 90 95 100 105 110 115 120 125 130 135

5. In a device of the character described, the combination of a movable main closure, movable closures adjacent said main closure, crank operating means connected by lost motion means to said closures for operating the same, and connecting means between said crank operating means and said main closure whereby said main closure may be operated to operate said closures.

10 6. In a device of the character described, the combination of associated closures, operating mechanism for one of said closures connected in operative relation to another of said closures, said mechanism including a pivoted member having a loose connection to said first named closure, crank members, one of said crank members being connected to each of said pivoted members and operable by another of said crank members, said last named crank member being operatively connected to said first named main closure.

7. In a device of the character described, the combination of associated closures, operating mechanism for one of said closures connected in operative relation to another of said closures, said mechanism including a pivoted member having a loose connection to said first named closure, crank members, one of said crank members being connected to each of said pivoted members and operable by another of said crank members, said last named crank member being operatively connected to said first named main closure.

8. In a device of the character described, the combination of a closure, operating mechanism therefor including a pivoted member having a loose connection to said closure, connected crank members, one of said crank members being connected to each of said pivoted members and operable by another of said crank members, said last named crank member being operatively connected to said first named main closure, and means for normally retaining said second named closures in guideway embracing position.

9. In a device of the character described, the combination of a main closure, a guideway associated with said main closure and adapted for supporting articles to be moved past said main closure, said guideway being located out of the path of said main closure, closures adjacent said guideway and arranged to embrace the same when in closed position, operating mechanism for said closures including pivoted members loosely connected to said closures, connected crank members, one of said crank members being connected to each of said pivoted members and operable by another of said crank members, said last named crank member being operatively connected to said first named main closure.

10. In a device of the character described, the combination of a main closure, a guideway associated with said main closure and adapted for supporting articles to be moved past said main closure, said guideway being located out of the path of said main closure, closures adjacent said guideway and arranged to embrace the same when in closed position, operating mechanism for said closures including pivoted members loosely connected to said closures, connected crank members, one of said crank members being connected to each of said pivoted members and operable by another of said crank members, said last named crank member being operatively connected to said first named main closure, means for normally retaining said second named closures in guideway embracing position.

5 ond named closures in guideway embracing position, and members secured to said last named closures and disposed in way of movement along said guideway for permitting operation of said closures regardless of the position of said first named main closure.

14. In a device of the character described, the combination of a main closure, a guideway associated with said main closure and adapted for supporting articles to be moved past said main closure, closures adjacent said guideway and arranged to embrace the same when in closed position, operating mechanism for said closures including pivoted members loosely connected to said closures; connected crank members, one of said crank members being connected to each of said pivoted members and operable by another of said crank members, said last named crank member being operatively connected to said first named main closure, means for normally retaining said second named closures in guideway embracing position, and members secured to said last named closures and disposed in way of movement along said guideway for permitting operation of said closures regardless of the position of said first named main closure.

15. In a device of the character described, the combination of a pivoted main closure, a guideway associated with said main closure and adapted for supporting articles to be moved past said main closure, said guideway being located out of the path of said main closure, slideable closures adjacent said guideway and arranged to embrace the same when in closed position, operating mechanism for said closures including pivoted members loosely connected to said closures, connected crank members, one of said crank members being connected to each of said pivoted members and operable by another of said crank members, said last named crank member being operatively connected to said first named main closure whereby operation of said first named main closure operates said second named closures, resilient means connected to said pivoted members and other resilient means connected to said second named crank member to normally urge said second named closures in guideway embracing position, and arcuate members secured to said last named closures and disposed in way of movement along said guideway for permitting operation of said closures independently of operation of said first named main closure or said operating mechanism.

16. In a device of the character described, the combination of a main door, a track disposed out of the path of said main door and on both sides thereof, and means including doors controlled by means connected to and releasable from said main door for selectively preventing access along said track, said doors having means allowing access along

said track independent of operation of said main door whereby access may be had through said doors when said second named means is released.

17. In a device of the character described, 70 the combination of a guideway, doors disposed on either side thereof and normally closing said guideway, a main closure, means operable by and directly connected to said main closure for positively operating said doors at any selected time, said means including a crank and links for moving said doors, and means for positively maintaining said doors in closed position.

18. In a device of the character described, 80 the combination of a guideway, doors disposed on either side thereof and normally closing said guideway, a main closure, means operable by and directly connected to said main closure for positively operating said doors at any selected time, said means including a crank and links for moving said doors, means for positively maintaining said doors in closed position, and means for effecting movement of said doors without operation of 85 said doors by said first named means when said first named means is released from said main closure.

19. In a device of the character described, 95 the combination of a guideway, doors disposed on either side thereof and normally closing said guideway, means for operating said doors, said means including crank and link members and a loose connection to said doors for moving said doors and permitting 100 relative movement of said doors with respect to said means, and resilient means for maintaining said doors in closed position.

20. In a device of the character described, 105 the combination of a guideway, doors disposed on either side thereof and normally closing said guideway, means for operating said doors, said means including crank and link members and loose connections for moving and permitting adjustable movement of 110 said doors, and resilient means for maintaining said doors in closed position.

21. In an icebox, the combination of a main door, a guideway disposed above said main door and extending into said icebox, securing means movable along said guideway for conducting articles into said icebox, normally closed doors disposed in way of said securing means and on either side of and embracing said guideway for preventing leakage past said guideway, operating means for said doors including cranks and links, and releasable and adjustable means disposed between said main door and doors for operating said doors under predetermined conditions.

22. In an icebox, the combination of a main door, a guideway disposed above said main door and extending into said icebox, securing means movable along said guideway for conducting articles into said icebox, normally 120

closed doors disposed in way of said securing means and on either side of and embracing said guideway for preventing leakage past said guideway, operating means for said doors including cranks and links so connected to said doors that adjustable closed movement may be effected, adjustable means disposed between said first named main door and doors for operating said doors under predetermined conditions, and means on said doors allowing operation of said doors by said securing means independent of said first named main door.

Signed at East Chicago, Ind., this 27th
15 day of August, 1927.
